(57) CLAIM

The ornamental design for a combined magnifier and pen, as shown and described.

DESCRIPTION

FIG. 1 is a perspective view of a combined magnifier and pen, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is an operational perspective view of a point of a pen pushed.

The broken line disclosure in the various views is for environmental purposes only and does not constitute a part of the claimed design.
